CLAIM

The ornamental design for a camcorder case, as shown and described.

DESCRIPTION

FIG. 1 is perspective view of a camcorder case embodying our new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a perspective view thereof, showing an attached shoulder strap.

The broken line showing of a shoulder strap illustrates the portion of the design that forms no part of the claim.
